(57) **CLAIM**

The ornamental design for a bottle, as shown and described.

DESCRIPTION

The nature of this product is as a container, such as a container in the form of a bottle for holding and dispensing a liquid material, such as a personal care lotion.

FIG. 1 is a right, top front perspective view of a bottle embodying our new design;

FIG. 2 is a front elevational view thereof, the rear elevational view thereof being a mirror image of the front elevational view shown;

FIG. 3 is a left side elevational view thereof, the right side elevational view thereof being the mirror image thereof;

FIG. 4 is a top plan view thereof; and,

FIG. 5 is a bottom plan view thereof.

The broken lines representation of the bottle neck in FIGS. 1-3 and 5, are for illustration purposes only and form no part of the claim.
